FURNACE FOR FIRING PORCELAIN

Nat Gold, Newark, N. J., assignor to Nu-Dent
Porcelain Studios, Inc., New York, N. Y., a cor-
poration of New York

Application March 29, 1952, Serial No. 19,112

Term of patent 14 years

(Cl. D81—10)

To all whom it may concern:

Be it known that I, Nat Gold, a citizen of the United States, residing in Newark, Essex County, New Jersey, have invented a new, original, and ornamental Design for a Furnace for Firing Porcelain, of which the following is a specification; reference being had to the accompanying drawing, forming a part hereof:

Fig. 1 is a perspective view of a furnace for firing porcelain, embodying my new design, and

Fig. 2 is a top plan view thereof.

The end and back portions thereof are substantially plain.

I claim:

The ornamental design for a furnace for firing porcelain, as shown and described.

NAT GOLD.
